UNITED STATES PATENT OFFICE.

EDWARD C. R. ELLSWORTH, OF TOLEDO, OHIO.

DESIGN FOR A TABLE.

No. 40,191.

Specification for Design.

Patented July 27, 1909.

Application filed May 1, 1909. Serial No. 493,439. Term of patent 7 years.

To all whom it may concern:

Be it known that I, EDWARD C. R. ELLSWORTH, a citizen of the United States, residing at Toledo, Lucas county, Ohio, have invented a new, original, and ornamental Design for Tables, of which the following is a specification, reference being had to the accompanying drawing, forming part thereof.

The figure is a perspective view of an embodiment of my new design in a table.

I claim—

The ornamental design for a table, as shown.

EDWARD C. R. ELLSWORTH.
